(57) **CLAIM**

We claim the ornamental design for a remote control device, as shown and described.

DESCRIPTION

FIG. 1 is a front perspective view of a remote control device of the present invention;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines shown in FIGS. 1-4 and 7 represent the boundary of the claimed design.
